Des. 239,030
Patented Mar. 2, 1976

239,030

RECORD COMMUNICATIONS TERMINAL

Donald M. Genaro, Haworth, N.J., and Arthur A. Hagstrom, Hoffman Estates, and Charles R. Winston, Deerfield, Ill., assignors to Teletype Corporation, Skokie, Ill.

Filed Jan. 16, 1974, Ser. No. 433,938

Term of patent 14 years

Int. Cl. D14—02

U.S. Cl. D26—5 C

FIG. 1

FIG. 2

FIG. 3

FIG. 4

FIG. 5

FIG. 1 is a front, top and left side perspective view of a record communications terminal showing our new design;

FIG. 2 is a top plan view;

FIG. 3 is a rear elevational view;

FIG. 4 is a front elevational view; and

FIG. 5 is a right side elevational view.

We claim:

The ornamental design for a record communications terminal, substantially as shown.
